(57) **CLAIM**

The ornamental design for a flask holder, as shown and described.

DESCRIPTION

FIG. 1 is a perspective view of a flask holder according to my invention from the front and above, with the lid lowered;

FIG. 2 is a perspective view thereof from the front and above with the lid raised;

FIG. 3 is a perspective view thereof from the side and above with the lid lowered;

FIG. 4 is a top plan view thereof;

FIG. 5 is a bottom plan view thereof;

FIG. 6 is a front elevational view thereof, with the rear elevational view corresponding thereto;

FIG. 7 is a front elevational view thereof with the lid raised, and with the rear elevational view thereof corresponding;

FIG. 8 is a side elevational view thereof, with the view from the opposite side corresponding; and,

FIG. 9 is a side elevational view thereof, with the lid raised, and the view from the opposite side corresponding.
